UNITED STATES PATENT OFFICE.

WILLIAM M. POTTER, OF SYRACUSE, NEW YORK, ASSIGNOR TO E. C. STEARNS & CO., OF SYRACUSE, NEW YORK.

SAW-JOINTER.

SPECIFICATION forming part of Letters Patent No. 738,354, dated September 8, 1903.

Application filed October 9, 1902; Serial No. 126,543. (No model.)

To all whom it may concern:

Be it known that I, WILLIAM M. POTTER, a citizen of the United States, residing at Syracuse, in the county of Onondaga and State of New York, have invented certain new and useful Improvements in Saw-Jointers; and I do hereby declare the following to be a full, clear, and exact description of the invention, such as will enable others skilled in the art to 5 know which it appertains to make and use the same.

My invention relates to saw-jointers; and it consists in a new construction thereof by which the jointer is cheapened and simplified, made more convenient for use, and the number of parts reduced. Its essential features 15 are a jointer-frame, integral lugs thereon to engage with the file, a screw fitted to the frame, and a nut on the screw, said nut and screw being adapted to engage with the file 20 and retain it, respectively, in its two positions.

My invention is clearly shown in the drawings herewith, in which—

Figures I and II are elevations showing the file retained, respectively, in flat and edge 25 positions. Figs. III and IV are vertical and cross sections corresponding, respectively, to Figs. I and II.

In the figures, 1 indicates the jointer-frame provided with integral upper and middle 30 flanges 3 and 4, perforated to receive the screw 6, integral lugs 7, and ribs 8, and with two integral bearing-lugs 9. On the screw is arranged the nut 11, fitted to recess 12 in the frame.

35 13 indicates the lower flange, in a cut-away central portion of which is arranged the usual gage-plate.

The file is first arranged in the edge position to joint the teeth, in which it is retained 40 between the tip of the screw and the two engaging or bearing lugs, as shown in Figs. II and IV. A slight bend may be given to the file when desired by the pressure of the screw, which is often desirable to follow the edge of 45 the teeth. After the teeth have been filed and sharpened the file is set in the flat position on the ribs 8 and there securely clamped between the nut and the lugs 7 and is used to remove any feather-edge or bur left in filing 50 and to even the set perfectly.

Having thus described my invention, what I claim as new, and desire to secure by Letters Patent, is—

1. In a saw-jointer, the combination with the jointer-frame having a bearing-surface 55 and parallel flanges provided with holes to receive the screw, of a screw arranged in perforations in the flanges and adapted to bear with its tip against the side of the file and clamp it against the bearing-surface, a nut 60 threaded on the screw to engage with the edge of the file and a stop on the frame to engage with the nut when the screw-tip is forced against the file.

2. In a saw-jointer, the combination with 65 the frame having two integral, parallel flanges, correspondingly perforated, of the screw arranged in said perforations, and an angular nut fitted to the screw and having one of its sides adjacent to the frame so that it will not 70 rotate when the screw is turned.

3. In a saw-jointer, the combination with the frame having an integral central flange, an integral, upper flange parallel to the central flange and on one side thereof, an integral 75 bearing surface or surfaces on the other side of the central flange and a recess in the frame between the flanges and adjacent to the central flange, of a screw arranged in corresponding perforations in the flanges and having its 80 tip projecting toward the bearing surface or surfaces, and a nut fitted to the screw and having a portion arranged in the recess.

4. In a saw-jointer, the combination with the jointer-frame having parallel, integral, 85 upper and middle flanges, a substantially square, central recess between the flanges and adjacent to the middle flange, and two lugs arranged parallel to and below the middle flange, of a screw arranged in central perforations in the two flanges, and a nut fitted to the screw and having one side arranged in the recess.

In testimony whereof I affix my signature in presence of two witnesses.

WILLIAM M. POTTER.
